US00D802049S

(12) United States Design Patent (10) Patent No.: US D802,049 S
(45) Date of Patent: * Nov. 7, 2017

(54) TYPE FONT

- (71) Applicant: Apple Inc., Cupertino, CA (US)
- (72) Inventors: Antonio Cavedoni, Mountain View, CA (US); Maxwell O. Drukman, San Francisco, CA (US); Riccardo Lorusso, Cupertino, CA (US); Christian P. Wagner, Pleasanton, CA (US); Eric Lance Wilson, San Jose, CA (US)
- (73) Assignee: Apple Inc., Cupertino, CA (US)
- () Term: 15 Years
- (21) Appl. No.: 29/561,623
- (22) Filed: Apr. 18, 2016
- (51) LOC (10) Cl. 18-03
- (52) U.S. Cl. D18/24
- (58) Field of Classification Search
USPC D14/490; D18/24, 25, 26, 27, 28, 29, 30, D18/31, 32, 33; 40/446, 447, 450, 451; 101/398, 399; 345/33, 45

See application file for complete search history.
